UNITED STATES PATENT OFFICE.

JOHN MARTINSON, OF DULUTH, MINNESOTA.

CABLE GRIP.

1,405,307.

Specification of Letters Patent.

Patented Jan. 31, 1922.

Application filed April 8, 1921. Serial No. 459,554.

To all whom it may concern:

Be it known that I, JOHN MARTINSON, citizen of the United States, residing at Duluth, in the county of St. Louis and State of 5 Minnesota, have invented certain new and useful Improvements in Cable Grips, of which the following is a specification, reference being had therein to the accompanying drawing.

10 This invention relates to cable grips and has special reference to such a device used in connection with the anchor line of a stump pulling machine wherein it becomes frequently desirable to adjust the length of 15 such line.

I am aware that cable grips of this character, and of much the same mechanical combination are old, but my present invention more particularly resides in a locking 20 attachment for grips of this character, the principal object being to provide simple means whereby the grip is automatically held in its open adjustable position when the length of the cable passing therethrough 25 is being regulated.

Other objects and advantages will appear in the further description of the invention.

Referring to the accompanying drawing forming part of this application and in 30 which like reference characters indicate like parts;

Figure 1 is a side elevation of a cable grip with my improved lock attached thereto;

Figure 2 is an end elevation of the holding 35 jaws of the grip;

Figure 3 is an elevation of Figure 1 viewed from the side opposite to that of the holding jaws; and

Figure 4 is an elevation of the detached 40 locking member.

1 represents the normally stationary main body portion of the grip which comprises a metal bar having a hole 2 in one extreme end into which is to be attached a line or 45 cable by which the grip is made fast to a stump or anchor of any available character for holding the grip in stationary position.

Adjacent the opposite end of the body portion 1 are two spaced holes in which are 50 pivotally mounted bars or links, one pair of which is designated by the numerals 3 and the other pair by the numeral 4, each pair being, as before stated, pivotally attached to the bar 1 at the points 5 and 6 respectively.

55 These links normally extend at right angles to the body bar 1 and pivotally carry

intermediate of their free ends the two gripping jaws 7 and 8, these jaws being spaced apart and having concaved opposed faces as illustrated at 9, intermediate of which the 60 cable which leads to the stump puller or other like device is engaged, and, it being well known to those versed in the art of manipulating such devices that under ordinary circumstances when a pulling cable 65 is thus installed intermediate of the jaws 7 and 8 and a stress applied thereto when the body portion 1 is securely anchored, the jackknifing effect of the pivotally united portions of the grip will cause the jaws 7 70 and 8 to forcibly impinge the cable and hold it securely against slipping. Under these circumstances when it is desired to release the hold of this form of grip it becomes necessary to readjust the relative position 75 of the pivotal portion of the grip so that the jaws will be slightly separated and release their hold upon the pulling cable, when, if it is so desired, the pulling cable may be drawn through the jaws either to be 80 wholly released therefrom or if drawn towards the anchor when still attached to the puller may be thus shortened for a subsequent pull as for example when after the first pulling stress has been accomplished 85 and the tackle of the stump puller has become shortened in relation to the subject being pulled that such shortening of the anchor line becomes essential.

Now in the folding together of the grip 90 for releasing the hold upon the pulling line I have provided means whereby such folding action is limited in that shoulders 10 are provided on either side of the body arm 1 adjacent the upper edges of the links 3 95 and which shoulders are so formed as to permit the links 3 to assume only a position at substantially right angles to the link 1 during the act of folding together of the grip, and, while the links are in this relative position to the arm 1 the jaws 7 and 8 are in 100 their maximum spaced relation to each other.

A pivotal pin 11 is installed through the links 3—3 centrally thereof, and spaced 105 away from the inner edge of the arm 1. Upon this pin is pivotally mounted the pawl or stop 12, it being a flat elongated strip of metal having two spaced ears 13—13 projecting substantially at right angles from 110 one face thereof through which are suitable holes for mounting upon the pin 11. This

pawl is of a width to just loosely fit in intermediate of the links 3 and is made of a length so that the lower end projects downwardly intermediate of the links 4 where it is designed to cooperatively engage under suitable circumstances a notch 14 in the lower inner edge of the arm 1 and adjacent the pivotal connection 6 of the links 4, the upper end 15 of the pawl extending outwardly beyond the outermost edges of the links 3 where it may be manually manipulated for adjusting purposes.

A second pin 16, similar to the pin 11, is installed through the links 3-3 and spaced somewhat away from the latter and about this pin is installed one end of a flat spring 17, which, intermediate of its ends, is wound about the pin 11 and extends downwardly with its free end engaging the back of the pawl 12 for holding the lower end of the latter at all times tightly against the inner edge of the body arm 1 for automatic engagement within the notch 14 when the adjustment of the grip permits of such. The relations of the pawl with the notch 14 are such that this engagement takes place when the links 3 and 4 are disposed substantially at right angles to the body arm 1, as illustrated in Figure 1 of the drawings.

When the pawl 12 is thus engaged within the notch 14 it is evident that the grip will not function as the jaws 7 and 8 are thus held in their maximum spaced position not forcibly engaging the pulling cable, and, being thus held, permits of free adjustment of the pulling cable intermediate of the jaws 7 and 8.

The object of the gripping jaws being thus held is readily discernible when it is considered how that it is frequently desired to shorten the length of the pulling line intermediate of the grip and the pulling device, as an operator stepping behind the grip and grasping the bite of the pulling line after the latter has been slacked away from the machine and the act of pulling towards the anchor will tend to fold the grip to the position shown in Figure 1 of the drawing when the pawl will automatically become engaged within the notch 14 and thus hold the grip in its open position for the free and unobstructed adjustment of the line, while in devices of this character, as before stated, not being provided with this automatic holding device,

it becomes very awkward and inconvenient of adjustment under these circumstances.

After the desired adjusting or shortening of the pulling line has been accomplished all that is necessary to do to permit of the grip properly functioning is to manually release the pawl by pressing inwardly upon the free projecting end 15 thereof, thus counteracting the influence of the spring 17, which will allow the grip to jackknife, as before described, resulting in the secure holding of the pulling line.

Having thus described my invention, what I claim and desire to secure by Letters Patent, is as follows:

1. The combination with a cable grip of the character described comprising a main body portion to which the anchor line of a pulling cable is attached, and pairs of gripping links pivotally attached to said body portion, of a manually adjustable pawl carried by said grip for automatically holding the grip in released position, substantially as described.

2. A cable grip of the character described comprising a main body portion to one end of which a stationary anchor line may be attached, spaced bars or jaw holding links pivotally mounted on the body portion, shoulders on the body portion to prevent the links from closing inwardly towards the body portion beyond substantially right angles thereto, and manually adjustable means for automatically holding the links in such relative position to the body portion for the purpose described.

3. A cable grip of the character described comprising a main body portion to one end of which a stationary anchor line may be attached, spaced bars or jaw holding links pivotally mounted on the body portion, shoulders on the body portion to prevent the links from closing inwardly towards the body portion beyond substantially right angles thereto, and a spring operated manually adjustable pawl carried by the links for cooperative engagement with the body portion, substantially as and for the purpose described.

In testimony whereof I hereunto affix my signature in the presence of two witnesses.

JOHN MARTINSON.
